UNITED STATES PATENT OFFICE.

ERNEST J. DEUTSCH, OF NEW YORK, N. Y.

COMBINED TYPE-WRITING AND PRINTING MACHINE.

SPECIFICATION forming part of Letters Patent No. 660,149, dated October 23, 1900.

Application filed November 13, 1899. Serial No. 736,765. (No model.)

To all whom it may concern:

Be it known that I, ERNEST J. DEUTSCH, a citizen of the United States, and a resident of New York, county of New York, and State 5 of New York, have invented certain new and useful Improvements in a Combined Type-Writing and Printing Machine, of which the following is a specification, reference being had to the accompanying drawings, forming 10 a part thereof, in which similar letters and figures of reference indicate corresponding parts.

This invention relates to improvements in combined type - writing and printing machines, the object thereof being to provide a machine of this character which is adapted for effectively and rapidly producing a plurality of letters which all embody the same matter and are respectively supplied with a 20 distinctive superscription. The device is so constructed that the ink for printing both the body of the letter and the superscription is supplied from a common source, whereby a partly-printed and partly-type-written letter which has the distinctive appearance of a fully-type-written product is produced.

The invention will be hereinafter fully described and specifically set forth in the annexed claims.

30 In the accompanying drawings, forming part of this specification, Figure 1 is a vertical sectional elevation of my improved machine. Fig. 2 is a detailed longitudinal elevation taken on the line xx of Fig. 1. Fig. 3 is a longitudinal sectional elevation taken 35 on the line yy of Fig. 1, and Fig. 4 is an end elevation in detail of a part of the structure.

In the practice of my invention, as illustrated by the drawings, I employ, primarily, 40 a type-writing machine A, which embodies an ordinary sliding carriage B, a revoluble roller C, feed mechanism D, a keyboard E, and swinging type-bars F, the said structure being of any adapted construction having the 45 relative arrangement of its parts in operative position. Preferably the carriage B is supplied with a rack 1, which engages a pinion 2, the carriage sliding within a grooved support 3 and the pinion being mounted upon a 50 shaft 4, which is journaled through a projection 5, forming part of the grooved support 3. This shaft also carries a ratchet-wheel 6,

which engages a pawl 7 for revolving the said ratchet-wheel and the pinion 2 to feed the carriage B laterally. The pawl 7 is loosely 55 pivoted to a cross-bar g of a vertically-movable frame G, which slides in ways 8, formed upon the inner surfaces of the end walls of the framework H, which supports the type-writer mechanism, and this said frame is 60 maintained in a normally-upward position by means of springs 9, which rest in recesses h of a cross-beam H' of the frame H. This frame bears upon the respective under surface of each key-lever e , forming the keyboard 65 E, whereby when a lever e is forced downwardly, as illustrated by dotted lines, Fig. 1 of the drawings, the frame G and its connected pawl 7 will also be forced downwardly, the said pawl sliding freely over the teeth of 70 the ratchet-wheel 6 to a distance equal to the length of one of said teeth, whereby when pressure is released from the bar e the springs 9 will force the frame G upwardly, carrying the pawl back to its normal position and re- 75 volving the ratchet 6 and pinion 2 to the extent of one tooth, thus feeding the carriage B in the direction of the arrow x , Fig. 2 of the drawings.

In connection with each key-lever e , by 80 means of bell-crank levers I and connecting-rods i and i' , is a type-bar F, which has type f upon its outer end. A plurality of these type-bars are used and they are pivoted upon an arched or segmental shaft or support J in 85 such relative arrangement that the type upon each bar will strike a common center when it is pressed downwardly, as illustrated by dotted lines, Fig. 1 of the drawings. The bell-crank levers I are also pivoted upon an 90 arched or segmental support I', the two said arched supports being secured to the frame H by any suitable means. In the drawings I have shown a single type-bar and the connected means for operating it; but it is obvious 95 that a plurality of said type-bars can be arranged upon the arched support J in a manner common to the art of constructing type-writers.

An auxiliary roll C' is journaled to the side 100 walls of the frame H for the purpose of feeding paper to the cylinder forming part of the printing-machine, as will be hereinafter described. This roll is secured to a shaft c ,

which is journaled within U-shaped grooves c' , formed in hangers h' of the frame H , whereby the said roll can be thrown in a forward direction out of contact with the cylinder, as illustrated by dotted lines, Fig. 1 of the drawings. An idler-roll C' is journaled beneath the roll C and connected therewith by means of flexible belts K , which are employed to feed the paper to the cylinder. The frame carrying the type-writing apparatus is slidably mounted upon a base L , and it is connected with the rigid frame M of the printing mechanism by means of bolts l and nuts l' , the sliding frame H being maintained in a normally-forward position and pressed away from the rigid frame M by means of spiral springs m .

The printing apparatus comprises a revolute type-cylinder N , a series of absorbent rolls n , a metallic roll O , an ink-fountain P , and a corrugated absorbent roll Q for supplying ink to the type f of the type-bars F . These said parts are all slidably mounted in the framework M , the cylinder N being journaled by means of its shaft n' within a sliding box n^2 . Each roll is also supported by means of a sliding box n^3 . The rolls n may be of any desired length; but the bottom roll which contacts with the type is only of a length equal to the width of the printed matter, so that it will contact with the type only. Spiral springs n^4 are employed to maintain the rolls in contact with each other and to govern the pressure. The said boxes supporting the rolls are adjusted vertically by means of adjusting-screws R and R' , which are threaded through the top plates m' of the frame M . Each screw R is supplied with an annular groove r , and these grooves engage forks p , secured to the end walls of the ink-fountain P for the purpose of adjusting the said fountain vertically, the fountain being further supported by means of projecting lugs p' , which engage grooves m^2 , formed in the end walls of the frame M . The top of the ink-fountain P is closed by means of an adjustable lid P' . This said lid bears upon the metallic roll O , and it can be adjusted up and down upon the ink-fountain P for the purpose of governing the flow of ink therefrom by means of the screws p^2 .

Connected to one end of the shaft n' , which carries the cylinder N , is a pinion 10, and this pinion communicates with pinions 11, which are connected, respectively, to each supporting-shaft of the rolls n , the roll O' also having a pinion connected to its shaft, whereby when rotary motion is given to the cylinder N by means of the crank 12 all the rolls will be caused to revolve in directions as indicated by the arrows, Fig. 1 of the drawings. The cylinder N is supplied peripherally with a segmental recess 13 for receiving the type 14 and the spacing-bars 15. This recess extends around the major portion of the cylinder and leaves only a small rib 16 extended across said cylinder. This rib acts as a guard or start-

ing-line for the first row of type when the same is being set. The end wall 17 of the cylinder N is provided with a series of segmental recesses 18 for engagement with the spacing-bars 15, and for the purpose of locking the spacing-bars within the recesses 18 each of these said recesses is supplied with a tongue 18^a, and these said tongues engage 75 grooves 15^a of the spacing-bars 15. Surrounding the cylinder N and located opposite to the wall 17 is a sliding segment S , which is supplied upon its inner face with a series of recesses s for engagement with the spacing-bars 80 15 and upon its periphery with a sliding segmental plate S' to lock over the edges of the said spacing-bars. This plate is secured to the segment S by means of screws 19, which engage grooves 20, whereby said plate can be 85 readily moved back and forth, as illustrated by dotted lines, Fig. 3 of the drawings. To adjust the segment back and forth upon the cylinder N , I employ a plurality of stationary screws T , secured to the end wall 17^a of the 90 cylinder N , and a plurality of sleeves T' , the said sleeves being threaded to the screws T , and engaging recesses in the outer face of the sliding segment S , whereby said segment can be forced tightly against the type after it is 95 set to maintain it in rigid connection with the cylinder.

To hold the cylinder in an arbitrarily-selected normal position and automatically stop movement of the same after a revolution has 100 been made, a spring-bolt 21 is supplied, and this bolt engages a recess 22 in the outer surface of the end wall 17 of the cylinder N .

In the operation and use of the device the body of a letter—for instance, a "circular letter" adapted to be sent to a large number of persons—is set up on the cylinder N by means of the type 14 and the spacing-bars 15. The type and bars are then securely locked in position by means of the sliding segment S , 105 whereby the cylinder is ready for printing in a manner common to all rotary printing mechanism. The fountain P is then supplied with ink of any suitable color, and said ink is communicated through the medium of the 110 several rolls to the cylinder, the corrugated roll Q also being supplied with ink for the purpose of feeding the type-writer. The corrugations of this roll Q are of such shape as to allow the type F in its descending movement to strike squarely and receive a supply 115 of ink over its entire face. To produce the letters, the type having been properly set, an operator will address and date each letter by means of the type-writing mechanism and the 120 sliding carriage and roll in the customary manner, the type-bars F in their downward sweep taking ink from the corrugated roll at each stroke. Having dated and addressed the letter, the operator removes it from the type- 125 writer by hand and then passes the same between the roll C' and the cylinder N , at the same time revolving said cylinder by means of the crank 12, the paper being fed and se- 130

curely maintained in contact with said cylinder by means of the flexible belts K. The letter being printed, it will discharge beneath the roll C² and in a forward direction, whereby it can readily be removed.

5 By the use of this machine it is obvious that circular letters can be not only rapidly addressed and printed, but owing to the fact that the ink for the type-writing and printing comes from a common source each letter will have the exact appearance of a fully-type-written letter.

10 I do not confine myself to the specific details of mere mechanical construction and relative arrangement, as herein shown and described, as it is obvious that under the scope of my invention I am entitled to slight modifications of construction.

15 Having thus described my invention, what I claim as new, and desire to secure by Letters Patent, is—

20 1. As a printing apparatus, the combination of a type-writing machine and a rotary printing mechanism, and a corrugated roll 25 rotated between the printing-press and the type-writing machine to supply ink to the type-bars of the type-writing machine, and means supporting the two structures, substantially as shown and described.

25 30 2. A printing-machine comprising a type-cylinder, ink-carrying rolls, an ink-fountain and a corrugated roll for supplying ink to a type-writer, substantially as shown and described.

35 3. In a printing-machine, the combination of a type-cylinder, removable type therefor and means for securing the same, a series of ink-carrying rolls, a vertically-adjustable ink-fountain communicating with said rolls, and 40 a corrugated roll for supplying ink to the

type-bars of a type-writer, substantially as shown and described.

4. As a combined printing-machine and type-writer, the combination of a revoluble cylinder having a segmental recess therein, 45 removable type engaging said recess and means for securing said type, a series of ink-carrying rolls, a vertically-adjustable ink-fountain, an adjustable lid thereon, a corrugated roll, and a type-writing machine in 50 such relative arrangement with said roll as to take ink therefrom automatically during the process of operating said type-writing machine, substantially as shown and described.

5. The combination of a type-writing machine embodying type-bars, a keyboard, a sliding carriage and roll, feed mechanism and an auxiliary roll, all mounted upon a sliding frame, with a rotary printing mechanism embodying a revoluble cylinder, movable type 55 therefor and means for fastening said type, a series of ink-carrying rolls, a vertically-adjustable ink-fountain for feeding said rolls and a vertically-adjustable corrugated roll engaging said rolls and located between them 60 and the type-writing machine, whereby the type-bars of the type-writing machine engage said corrugated roll to take ink therefrom during the process of operating the type-writing machine, substantially as shown and 65 described.

In testimony that I claim the foregoing as my invention I have signed my name, in presence of two witnesses, this 8th day of November, 1899.
